PNEUMATIC THREAD HOLDER FOR WEFT
REPLENISHING LOOMS

Richard G. Turner, Worcester, Mass., assignor to
Crompton & Knowles Loom Works, Worcester,
Mass., a corporation of Massachusetts

Application October 18, 1947, Serial No. 780,674

12 Claims. (Cl. 139—247)

1

This invention relates to improvements in weft replenishing looms and it is the general object of the invention to provide a pneumatic thread holder so constructed as to prevent objectionable movement of weft ends leading from reserve bobbins into the thread holder to the end that abrasion and slackness may be reduced to a minimum.

Weft replenishing mechanisms operate with a plurality of reserve bobbins having weft ends which lead to some form of thread holder. Heretofore I have proposed a pneumatic type of thread holder which has gone into general use more particularly in connection for looms weaving fabrics made of fine yarns. Subatmospheric pressures are provided by a pump having a piston which is reciprocated by the lay of the loom, and because of the nature of the pump the partial vacuum within the thread holder is created intermittently with intervening periods during which atmospheric pressure is restored within the holder. In a thread holder of this type there is some likelihood that elastic yarns will be drawn into the thread holder when subatmospheric pressures are created and then have a slight retrograde movement back toward the magazine when normal atmospheric pressures exist. This constant back and forth motion of the threads is likely to abrade them with resultant breakage, and the threads are also likely to become slack at a time when the lay is moving forwardly under them in a position to engage and break them.

It is an important object of the present invention to provide an improved form of thread holder constructed with holding means within the air passage of the holder the purpose of which is to prevent the aforesaid retrograde movement of the weft ends incident to the alternating conditions of atmospheric and subatmospheric pressures within the holder.

It is a further object of the invention to provide a pneumatic thread holder including a tube having an intake mouth to receive the weft ends and having a baffle or the like within the tube spaced from the intake mouth and in position to engage the weft ends and hold them against retrograde movement. The baffle may have a toothed or serrated edge, or it may be so placed as to produce at least one bend in the weft threads, or both of these features may be utilized.

More specifically it is an object of the invention to provide a thread holder tube one end of which is partly closed by a plate presenting a smooth rounded edge facing away from the reserve bobbins and around which the weft ends ex-

2

tend as they enter the tube, and provide a baffle secured in stationary position within the tube and having preferably a serrated edge facing in a direction opposite to that in which the aforesaid smooth edge faces and so located as to create a bend in the weft ends. One or more internal baffles may be used depending upon the type of weft being woven. The thread holder is made so that tubes of different types can be interchanged.

10 With these and other objects in view which will appear as the description proceeds, my invention resides in the combination and arrangement of parts hereinafter described and set forth.

In the accompanying drawings, wherein two forms of the invention are shown,

Fig. 1 is a side elevation of the upper forward part of a loom having my invention applied thereto, the lay and shuttle box being shown in section,

20 Fig. 2 is an enlarged side elevation of the preferred form of the thread holder as shown in Fig. 1, parts being broken away,

Fig. 3 is a vertical section on line 3—3 of Fig. 2 taken transversely of the axis of the thread holder tube,

Fig. 4 is a horizontal section on line 4—4 of Fig. 2,

Fig. 5 is a view similar to Fig. 2 but showing a modified form of the invention,

30 Fig. 6 is a horizontal section on line 6—6 of Fig. 5,

Fig. 7 is an enlarged end elevation of the intake mouth end of the tubes and the cross plate which forms one edge of the mouth,

35 Fig. 8 is a plan view looking in the direction of arrow 8, Fig. 7, and

Figs. 9 and 10 are diagrammatic views of the weft ends showing the bends therein formed, respectively, in the preferred and modified forms

40 of the invention.

Referring to Fig. 1, the loom frame 10 supports a magazine M which in the present instance is provided with front and back stacks 11 and 12 of bobbins from which weft ends W extend to the thread holder designated generally at H. The lay 13 is provided with a shuttle box 14 to receive the shuttle S containing a bobbin B. The transfer arm 15 is provided to transfer the lowest bobbin in one or the other of the stacks 11 and 12 into the shuttle S upon depletion of the weft of bobbin B. The magazine can be rocked by means of mechanism 16 operating in timed relation with the shifting shuttle boxes not shown but located at the opposite end of the loom. The lay is reciprocated backwardly and forwardly by means

55

of a connector 17 driven by the usual top or crank shaft not shown.

The loom supports an air cylinder 20 having a piston 21 attached by rod 22 to the upper end of a lever 23. A connecting rod 24 between the lay and lever 23 moves the piston rearwardly when the lay is moving from front to back center to create a partial vacuum or subatmospheric pressures within a hose or tube 25. When the lay is moving forwardly the pump is ineffective to create subatmospheric pressures and normal atmospheric pressure is momentarily restored in the pneumatic system.

A thread collector C is held in fixed position by a stand 26 secured to the loomside and has its hollow interior pneumatically connected with the tube 25. The collector includes in its construction a base 28 which affords support for the improved forms of thread holder to be described.

The thread holder is made with a thread receiver 30 having upwardly extending diverging horns 31 and 32 defining between them a downwardly tapered space 33 terminating in a vertical upwardly opening thread slot 34. When new bobbins are placed in the magazine their weft ends are dropped between the horns 31 and 32 and into the slot 34 from which position they were drawn pneumatically toward the thread collector C and are preferably of such length that they may become entangled with other weft ends within the collector which serve as an anchorage.

The matter thus far described is of known construction and may be for instance as shown in my prior Patent No. 2,199,353.

In the preferred form of the invention I use a tube 40 which is secured to the base 28 by means of a screw or the like 41, see Fig. 1. This tube extends forwardly beyond the base 28 as suggested for instance in Fig. 4 to afford support for the aforesaid receiver 30 and terminates near the slot 34. Extending part way across the end of the tube adjacent to slot 34 is a plate 42 having a preferably straight smooth rounded edge 43 which faces in a direction away from the magazine, or away from the direction from which the weft threads W approach the tube, see Fig. 4. This plate together with the right hand part of the tube as viewed in Fig. 7 forms an intake mouth 45 having a straight side defined by the edge 43.

Located within the tube and secured thereto in stationary position and spaced from the plate 42 is a baffle 46 shaped more or less as shown in Fig. 4 and having an edge 47 which is serrated or provided with teeth 48. These teeth point in a direction opposite to that in which the smooth surface 43 faces, and the baffle preferably extends across the tube far enough to produce a bend B1 in the weft ends at the right of the straight parts thereof indicated at 49 in Fig. 4. The smooth edge 43 and serrated edge 47 are preferably parallel to each other and may be located to produce the desired amount of bend in the weft ends extending through the tube.

In the operation of the preferred form of the invention the weft ends are dropped into the slot 34 as already described and upon backward movement of the lay the pump causes an inrush of air into the intake mouth 45 to draw the weft ends into the tube. The weft ends bend around the smooth surface 43 and then extend along and in engagement with the notch or serrated edge 47, and thence to the thread collector C. When the piston of the pump is moving forwardly and the air pressures within the tube temporarily return to normal atmospheric pressure the weft

ends due to their elasticity may tend to have a retrograde movement in a direction toward the magazine, but the baffle resists such movement due partly to the fact that the weft ends are bent and partly to the holding action of the serrated edge 47.

In the modified form of the invention shown in Figs. 5 and 6 the tube 50 is provided with end plate 42 as in the preferred form, and a baffle 51 similar to but of somewhat different form from baffle 46 is secured within tube 50 and provided with a serrated edge 52. In addition, there is a second baffle 53 which faces in a direction opposite to the direction in which baffle 51 faces. This second baffle has an edge 54 which may be either smooth similar to edge 43, or serrated as are edges 47 and 52. In Fig. 6 the second baffle 53 is shown with a serrated edge and in such position as to produce a second bend B2 in the weft ends within the tube 50 to the right of the straight parts 55 thereof.

The baffles may be secured in any desired manner to the interior of their respective tubes and are preferably stationary. The plate 42 which is used in both forms of the invention may be set into a notch 56 cut in that end of the tube adjacent to the slot 34 and held in position by welding, brazing or in any other approved manner, see Fig. 8. When the weft being used requires the preferred tube 40 the latter will be held in base 28 by set screw 41, but if a type of weft is used requiring greater holding action the tube 50 can be substituted for the tube 40. In both cases the tube will be set so that the smooth edge 43 will face in a direction away from the magazine as shown in Figs. 4 and 6 and at least one baffle will face in the opposite direction. The edges of the baffles are preferably parallel to edge 43.

From the foregoing it will be seen that I have provided a simple form of thread holder including a tube one end of which is partly closed by plate 42 to form an intake mouth having a straight rounded smooth edge 43 facing away from the magazine. It will also be seen that at least one baffle is located within the tube at a point spaced from the intake mount and is so located as to produce a bend in the weft ends tending to resist their retrograde movement toward the intake mouth. Also, the baffle can be made with a serrated edge formed with teeth which engage the weft ends to prevent them from moving toward the intake mouth. When two baffles are used as in the modified form of the invention one or both may be provided with serrated edges, but the edges whether serrated or not will be so related as to produce a plurality of bends in the weft ends the effect of which is to impede retrograde movement of the weft ends. All of the edges 47, 52 and 54 are preferably parallel, and the serrations in addition to preventing retrograde movement also assist in holding the threads in spaced relation and near the center of the stream of air moving through the tube.

Having thus described my invention it will be seen that changes and modifications may be made therein by those skilled in the art without departing from the spirit and scope of the invention and I do not wish to be limited to the details herein disclosed, but what I claim is:

1. In a pneumatic thread holder for the weft ends of reserve bobbins in a weft replenishing loom having a hollow thread collector in which subatmospheric pressures exist, a tube having one end in pneumatic communication with the thread collector and having a thread intake mouth at

the other end thereof, and means within the tube presenting a serrated edge formed with teeth positioned to engage threads in the tube and resist movement thereof toward the intake mouth and also hold the threads in spaced relation.

2. In a pneumatic thread holder for the weft ends of reserve bobbins in a weft replenishing loom having a hollow thread collector in which subatmospheric pressures exist, a tube having one end in pneumatic communication with the thread collector and having a thread intake mouth at the other end thereof, and means within the tube presenting a serrated edge formed with teeth positioned to engage threads in the tube and bend said threads to resist movement thereof toward the intake mouth and also hold the threads in spaced relation.

3. In a pneumatic thread holder for the weft ends of reserve bobbins in a weft replenishing loom having a hollow thread collector in which subatmospheric pressures exist, a tube having one end in pneumatic communication with the thread collector, means partly closing the other end of the tube and defining an intake mouth having a smooth substantially straight edge around which the weft ends bend as they enter the tube, and means within the tube intermediate the ends thereof presenting a serrated edge formed with teeth placed to engage the weft ends as they extend from said intake mouth to said thread collector and effective to resist movement of weft ends within the tube toward said intake mouth and also hold the threads in spaced relation.

4. In a pneumatic thread holder for the weft ends of reserve bobbins in a weft replenishing loom having a hollow thread collector in which subatmospheric pressures exist, a tube having one end in pneumatic communication with the thread collector, means partly closing the other end of the tube and defining an intake mouth having a smooth substantially straight edge facing away from the bobbins and around which the weft ends bend as they enter the tube, and means within the tube intermediate the ends thereof presenting a serrated edge facing toward the bobbins and placed to engage and bend the weft ends as they extend from said intake mouth to said thread collector and effective to resist movement of weft ends within the tube toward said intake mouth.

5. In a pneumatic thread holder for the weft ends of reserve bobbins in a weft replenishing loom having a hollow thread collector in which subatmospheric pressures exist, a tube having one end in pneumatic communication with the thread collector, a plate extending partly across the other end of the tube and having a smooth substantially straight edge which with the tube defines for the weft ends an intake mouth the straight part of which is toward the bobbins, means within the tube between the ends thereof presenting a substantially straight serrated edge facing in a direction opposite to the direction in which said smooth edge faces and so located as to produce a bend in weft ends extending from the intake mouth to said thread collector and resist movement of threads in engagement therewith toward said intake mouth.

6. In a pneumatic thread holder for the weft ends of reserve bobbins in a weft replenishing loom having a hollow thread collector in which subatmospheric pressures exist, a tube having one end in pneumatic communication with the thread collector, a plate extending part way across the other end of the tube and with the latter forming

an intake mouth for the weft ends, said plate having a smooth rounded edge facing away from the direction from which the weft ends approach the intake mouth, and a baffle within the tube spaced from said plate and having a serrated edge parallel to said smooth edge but facing in a direction opposite to that in which said smooth edge faces.

7. In a pneumatic thread holder for the weft ends of reserve bobbins in a weft replenishing loom having a hollow thread collector in which subatmospheric pressures exist, a tube having one end in pneumatic communication with the thread collector, a plate extending part way across the other end of the tube and with the latter forming an intake mouth for the weft ends, said plate having a smooth rounded edge facing away from the direction from which the weft ends approach the intake mouth, and a pair of spaced baffles within the tube arranged along the length thereof, one of said baffles having a serrated edge substantially parallel to said smooth edge, and said baffles facing in opposite directions.

8. In a pneumatic thread holder for the weft ends of reserve bobbins in a weft replenishing loom having a hollow thread collector in which subatmospheric pressures exist, a tube having one end in pneumatic communication with the thread collector, a plate extending part way across the other end of the tube and with the latter forming an intake mouth for the weft ends, said plate having a smooth rounded edge facing away from the direction from which the weft ends approach the intake mouth, and a pair of spaced baffles within the tube arranged along the length thereof, one of said baffles having a serrated edge substantially parallel to said smooth edge, and said baffles facing in opposite directions.

9. In a pneumatic thread holder for the weft ends of reserve bobbins in a weft replenishing loom having a hollow thread collector in which subatmospheric pressures exist, a tube having one end in pneumatic communication with the thread collector, a plate extending part way across the other end of the tube and with the latter forming an intake mouth for the weft ends, said plate having a smooth rounded edge facing away from the direction from which the weft ends approach the intake mouth, and a pair of spaced baffles within the tube arranged along the length thereof, one of said baffles having a serrated edge substantially parallel to said smooth edge, and said baffles facing in opposite directions, the baffle adjacent to said plate having its edge facing in a direction opposite to that in which said smooth edge faces.

10. A tube for the pneumatic thread holder of a weft replenishing loom, said tube having one end partly closed by a transverse plate having a straight smooth rounded edge, and a baffle within the tube having a serrated edge facing in a direction opposite to that in which the smooth edge faces.

11. A tube for the pneumatic thread holder of a weft replenishing loom, said tube having one end partly closed by a transverse plate formed with a smooth rounded substantially straight edge, and a baffle secured within the tube spaced from said plate and formed with a serrated edge substantially parallel to said smooth edge and facing in a direction opposite to that in which said smooth edge faces.

12. A tube for the pneumatic thread holder of

a weft replenishing loom, said tube having one end partly closed by a transverse plate formed with a smooth rounded substantially straight edge, and a pair of spaced baffles within the tube arranged along the length thereof, said baffles having thread engaging straight edges parallel to said smooth edge and facing in opposite directions, the edge of at least one of said baffles being serrated.
